UNITED STATES PATENT OFFICE.

ARTHUR W. MINNEY, OF STOCKTON, CALIFORNIA.

EGG BEATER AND MIXER.

Application filed March 24, 1922. Serial No. 546,418.

To all whom it may concern:

Be it known that I, ARTHUR W. MINNEY, a citizen of the United States, and a resident of Stockton, in the county of San Joaquin and State of California, have invented certain new and useful Improvements in Egg Beaters and Mixers, of which the following is a specification.

The object of the invention is to provide an improvement of this character wherein the agitating or mixing of the substance being handled is carried out in a closed receptacle so as to be entirely clean and highly sanitary and which is so constructed and organized as to thoroughly beat or mix the ingredients whereby to procure a well beaten or thoroughly mixed product.

Another object is to provide an improvement of this character which greatly facilitates the carrying out of the beating or mixing action and provides not only for the beating of eggs, coatings, frostings, thickenings, cake-doughs or the like but also for the mixing of mayonnaise, thick chocolates and custards or the like.

Another object is to provide an improved beater which may be readily set up upon the table, shelf, bench or the like and which may be conveniently taken down and stored when not in use.

Another object is to provide an improvement of this character which is of simple and durable construction, reliable in operation and easy and comparatively inexpensive to manufacture.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a detail perspective view of the preferred embodiment of the invention, certain of the parts being shown disassembled and certain parts being omitted for the sake of illustration;

Figure 2 is a view, partly in vertical section and partly in elevation of the beater or mixer;

Figure 3 is a detail perspective view of the complementary part of the bed or table of the machine.

Referring to the drawings wherein for the sake of illustration is shown the pre-

ferred embodiment of the invention, the numeral 10 designates generally the frame which includes a horizontal base bar 11 having integrally formed therewith at one end 60 an angular bar 12, the horizontal portion 12^a of which is coplanar with the underlying portion 11^a of the base bar 11. The underlying portion 11^a has threadedly connected thereto a clamping screw 13, one end 65 of which is formed to constitute a handle and the other end of which carries a clamping plate 14, the clamping plate 14 and the horizontal portion 12^a of the annular bar 12 being adapted to clamp or grip the projecting ledge of the table, shelf or the like, indicated at T in Figure 2. The frame 10 also has integrally formed therewith a standard 15 which extends vertically and which is arranged at the end of the base bar remote from the clamping screw 13. A skeleton, table or bed 16 is provided and preferably is made up of horizontally extending flat portions 17 and 18 and an arcuate or semicircular connecting portion 19 to which 70 a complementary and removable portion 20 (see Figure 3) is adapted to be secured by means of rivets or other suitable fastening means, these rivets or fastening means operating through openings 20^a formed in the 75 ends of the brace bar and openings 17^a and 18^a formed in the horizontal portions 17 and 18 of the table. The bed or table 16 is integrally formed with the standard 15 and is also supported by means of a vertical brace bar 21 and an angular brace bar 22 extending from the base bar 11 and the angular bar 12 respectively as clearly shown in the drawings. A receptacle or container 25 is supported upon the table 16 and is 80 adapted to contain the substance or substances to be beaten or mixed as the case may be. This receptacle 25 is preferably of cylindrical form and is provided with a cover 26 having a depending flange 27 85 spaced slightly inward from its periphery and adapted to engage the inner peripheral wall of the receptacle to completely close the upper open end of the receptacle when 90 this is desired. A handle 28 is fitted to the 95 cover.

Means is provided for releasably securing the receptacle to the frame and preferably comprises a pair of pins 30 welded or otherwise suitably secured to the base of the 100 receptacle and depending downwardly therefrom. These pins 30 are adapted to be re-

ceived in sockets 31 provided therefor in the portions 17 and 18 of the bed. The means for securing the receptacle to the frame also includes a laterally extending pin 32 carried by the peripheral wall of the receptacle adjacent the upper end thereof and cooperable with the V-shaped socket or notch 33 formed in the upper end of the standard 15, the pin 32 being also welded or otherwise suitably secured to the receptacle 25.

The receptacle 25 is provided at its center with a tube or cylindrical casing 35 which has its lower end suitably secured or formed integral with the base of the receptacle and which upstands from the base, the upper end of the tube terminating a substantial distance below the upper end of the receptacle, as shown in Figure 2. Within the tube or cylindrical casing 35 bearings 36 and 37 are arranged, and in these bearings an operating shaft 38 is journaled, the operating shaft being supported at its lower end in a step or spindle bearing 39 and being provided with a thrust bearing in the form of a collar 40 secured to the shaft by a pin 41 and operating between the portion 12^a of the angular bar 12 and a lateral arm or lug 42 integrally formed with the annular brace bar 22 and extending parallel to the portion 12^a of the portion 12.

The upper end of the operating shaft 38 is squared, as at 38^a and this squared portion of the operating shaft fits in a squared opening 45^a provided in the hub 45 of the beater or mixer, designated generally at 46. The beater or mixer 46 includes angular arms 47 integrally formed with the hub 45 and carrying a plurality of beater blades or fingers, indicated at 48. Any desired number of beater blades or fingers may be provided but preferably they are provided in the number and in the manner shown in the drawings. The hub 45 of the beater is elongated, as shown in Figure 2, and the lower end of this elongated hub rotatably abuts the adjacent face of the bearing 36. The tube 35 has its upper end provided with an inturned flange 35^a which snugly engages the periphery of the hub 45 although permitting free rotation of the hub with respect thereto. A cap or hood 50 is secured to the hub of the beater by suitable fastening means, such as by means of rivets 51 and extends down around but spaced from the tube 35 and in this manner displacement of the substance being beaten or mixed from the receptacle or interior of the tube is prevented.

Means is provided for rotating the operating shaft so as to actuate the beater, and this means preferably includes a relatively small beveled gear 55 fixed to the operating shaft, as at 56 and meshing with a relatively large beveled gear 57 secured, as at

58 to one end of a jack or countershaft 59 journaled in bearings provided therefor in the frame and rotated from a hand crank 60 by means of a large gear 61 secured, as at 62, to the crank shaft of the hand crank and meshing with a small gear 63 secured, as at 64 to the jack or countershaft 59. The crank shaft 60 and the jack shaft 59 are mounted in suitable bearings provided in the frame 10 and they are also supported and constrained to their proper field of action by means of a bracket 66 having offset bearing portions 67 and 68 provided thereon and secured at its ends by means of screws 69. The bracket 66 serves not only to rotatably journal the shaft 59 and 60 but it also prevents endwise displacement thereof thus functioning as thrust bearings for these shafts. The hand crank 60 preferably includes a hand grip or hold 85 70 75 80 85 90 95 100 105 110 115 120 125 130

In operation, the machine is clamped upon a table, shelf or the like by manipulating the clamping screw 13. The receptacle 25 is then positioned on the table 16 and the beater is assembled on the operating shaft. The materials or substances to be beaten or mixed may be placed in the receptacle before or after assembling the beater therewith as desired. After the substances to be mixed or beaten are placed in the receptacle and the beater has been assembled with the operating shaft the cover is placed in position, as shown in Figure 2. The hand crank 60 may then be turned to carry out the beating operation. When this hand crank 60 is turned its gear 61 causes the gear 63 to rotate and the gear 63 causes the shaft 69 to rotate which in turn rotates the operating shaft 38 through the beveled gears 57 and 55. The rotation of the operating shaft causes the beater to revolve and the beater fingers thoroughly mix or beat the substances within the container. The gear employed to transmit the rotation of the hand grip to the beater is such as to speed up the beater and so as to enable the operator to carry out the beating or mixing operation with the least effort and with the greatest efficiency.

I claim:

1. In a machine of the character described, a frame including a base bar, a standard, a table connected with the standard, a vertical brace bar between the base bar and the table, said frame being provided with attaching means including an angular bar connected with the base bar, an angular brace bar between said angular bar and the table, a receptacle mounted upon the table, an operating shaft, said frame having a spindle bearing receiving the lower end of the operating shaft, an arm carried by the angular bar and having an opening through which the operating shaft passes, a cover fixed to said shaft and

- abutting the angular bar at its lower side and the arm its upper side, a beater carried by said operating shaft and arranged within the receptacle, and means carried by said 5 frame for rotating said shaft.
2. In a machine of the character described, a frame including a table having sockets therein and a standard having a socket at its upper end, a receptacle having depending 10 pins adapted to be received in the sockets of the table and a laterally extending pin adapted to be received in the socket of the standard and a removable beater adapted to be operatively mounted in said receptacle 15 when the same is assembled with the table and with the standard.
3. In a machine of the character described, a frame, a receptacle supported upon said frame, a vertical tube arranged in the receptacle, spaced bearings disposed within the tube, one of the bearings being located adjacent but slightly spaced from the upper 20 end of the tube, an operating shaft journaled
- in said bearings and projecting beyond the upper bearing, a beater having a hub fitted 25 on the upper end of the shaft and extending down into the tube, the lower end of the hub abutting the adjacent bearing to limit the downward movement of the beater on said shaft.
4. In a machine of the character described, a frame, a receptacle supported upon the frame and including a base, a vertical tube upstanding from the center of the base, an operating shaft extending up through the 30 tube and journaled upon the frame at its lower end, bearing collars arranged within the vertical tube and rotatably accommodating said operating shaft, one of the bearing collars being located at the lower end of 35 the tube, and means for actuating said shaft including a driven gear fixed to the operating shaft and engaging the lower bearing collar.

ARTHUR W. MINNEY.
